ILLINOIS.

BANK OF LOCKING SWITCH-KEYS.

No. 902,275.

Specification of Letters Patent.

Patented Oct. 27, 1908.

Application filed March 28, 1908. Serial No. 423,885.

To all whom it may concern:

Be it known that we, ELMER R. CORWIN and CHARLES A. BALS, both citizens of the United States of America, and residents of Chicago, Cook county, Illinois, have invented a new and useful Bank of Locking Switch-Keys, of which the following is a specification, reference being had to the accompanying drawings illustrating same.

10 Our invention relates to banks of switch keys of the push-button type, wherein any push-button that is depressed is automatically locked in depressed position, the depression of any other push-button of the bank 15 releasing the first depressed push-button, the last depressed push-button being automatically locked in depressed position until released by the depression of another push-button.

20 The principal objects of our invention are to provide a simplified construction in such a bank of locking keys; to provide an improved arrangement for automatically operating the locking bars of the several keys of 25 the bank; to provide an improved ringing arrangement for each of the keys of the bank; to provide improved means for operating the several plungers of the various keys of the bank, upon their release by the various locking bars; to provide improved means for 30 numbering or lettering each of the keys of the bank; and to provide improved means whereby the operation of the various keys, when released, is practically noiseless.

35 Other objects will be apparent from the following specification.

In the drawings, Figure 1 is a side elevation of a bank of locking switch keys constructed in accordance with the present invention, with portions shown in cross-section to show the interior construction of the apparatus; Fig. 2 is a right-hand end view of the bank of switch keys shown in Fig. 1, with portions shown in cross-section to show the 40 interior construction of the apparatus; and Fig. 3 is a plan view of the bank of switch keys shown in Figs. 1 and 2. Like characters refer to like parts in the several figures.

The bank of keys illustrated comprises one 50 or more spring-contact mounting strips 33 33 carried by formed sheet-metal portions 34 34 secured to the ends of the strips 33 33 and to the top plate 35, preferably by screws. Each of the strips 33 33 carries a plurality of sets 55 of spring-contact members, each set having

a plunger 36 made of insulating material, for operating the said contact members, each of the plungers 36 36 being connected by a vertical bar 37 which extends through the top plate 35, with a push-button 38 the depression of which depresses the plunger 36 and thereby operates the switch-contact members as will be hereinafter described. Each of the plungers 36 36 has a rod 7 extending therethrough, from the corresponding bar 37 60 into one of the strips 33 33, preferably as shown in Fig. 2, the said rod 7 having a coil spring 8 encircling same to automatically raise the plunger 36 out of connection with the corresponding set of spring-contact members when the push-button 38 and the bar 37 are released. To accommodate the rods 7 7 the strips 33 33 are drilled on their top edges 70 with holes slightly larger than the rods 7 7, and with larger holes 9 9 extending up from 75 the bottom edges thereof to meet the smaller holes at the top edges, to form bearings for the rods 7 7 at the top edges only of the strips 33 33. This construction in the strips 33 33 gives a free action to the rods 7 7, as the 80 latter do not bear against the interior portions of the strips 33 33 along the entire length of the inserted end portions of the rods 7 7.

The top plate 35 is provided with suitable 85 holes 10 10 for mounting the bank in place. On the underneath side of the plate 35 is secured a strip 11 of felt, or some other pliable material, for deadening the sound of the striking of the collars 12 12 of the bars 37 37 90 when the latter are released and forced upward by the coil springs 8 8. The collars 12 12, preferably formed of sheet metal and each having a tongue portion 32 riveted to the corresponding bar 37, are secured around the 95 bars 37 37 underneath the felt strip 11 to limit the upward movement of the push-buttons 38 38, when the bars 37 37 are released. It will readily be seen that the felt strip 11 100 practically makes the operation of the bars 37 37 noiseless, as it forms a cushion for each of the collars 12 12 when the bars 37 37 are released.

Each of the group of switch contacts comprises spring members 13, 14, 15, 16 and 17, 105 the spring members 15 and 16 being adapted to engage the spring members 14 and 17, respectively, when the corresponding plunger 36 is depressed to locking position, and the spring member 14 being adapted to engage 110

the spring member 13 when the plunger 36 is depressed still further. The spring member 15 is made somewhat longer than the spring member 16, so that it will engage the large upper portion 18 of the plunger 36 before the spring member 16 would engage the portion 18 if the plunger 36 were depressed far enough, so as to throw the spring member 14 into contact with the spring member 13 without operating the spring members 16 and 17 after they have come into contact with each other. This construction gives an easier action to the push-buttons 38 38 when same are depressed to cause the spring members 14 14 to engage the respective spring members 13 13.

The sheet-metal end portions 34 34 are provided with notches near their upper ends in which are slidably mounted longitudinal side bars 19 19, the latter being held together by a plurality of transverse locking bars 20 20 suitably riveted to the side bars 19 19. Each of the transverse bars 20 20 is for locking one or more of the push-button keys 38 38 of the bank in depressed position.

Each of the bars 37 37 is provided with two notches 21 22 therein, to accommodate the corresponding locking bar 20, the latter notch 22 being beveled at its upper edge to permit the depression of the push-button 38 to move the side bars 19 19 and the locking bars 20 20, as a unit, in the direction of arrow 23, against the action of the leaf spring 24 which is mounted to one of the end portions 34 34 and which bears against the transverse bar 25 carried by the side bars 19 19. The transverse bar 25 is preferably similar to the locking bars 20 20. The end strip 34 to which the spring member 24 is mounted is provided with a set screw 26 and a lock nut thereon, which set screw may be adjusted through the strip 34 against the spring member 24 to adjust the tension of the latter against the bar 25 as desired.

The depression of any one of the push-buttons 38 38 causes the beveled portion of the lower notch 22 of the corresponding bar 37 to engage the corresponding locking bar 20 and thereby move the side bars 19 19 and the locking bars 20 20 as a whole in the direction of arrow 23 until the locking bar 20 is able to drop into the notch 21 and thereby allow the spring member 24 to force the side bars 19 19 and the locking bars 20 20 as a whole in the direction of arrow 27 so that the locking bar 20 rests in the notch 21 of the depressed push-button key. In this locked position the spring members 15 and 16 of the depressed key engage the contact members 14 and 17, respectively, but the contact member 14 does not engage the contact member 13. If the depressed key is now further depressed the contact member 14 will be caused to engage the contact member 13. In telephone systems this latter depression of the

key generally closes a ringing circuit, while the former depression of the key, or the depression to locking position, generally closes a talking circuit. Now, if any of the other keys of the bank is depressed to locking position, as just described, the side bars 19 19 and the locking bars 20 20 will be moved as a whole by such depression in the direction of arrow 23 so that the locked key will be released and forced by the corresponding coil 75 spring 8 to the position shown in the drawings, the latter depressed key now being locked by its locking bar 20 in a depressed position. It will readily be seen that by this construction the depression of any one of the keys of the bank to locking position will release any of the other keys of the bank which have previously been locked in depressed position, and that any of the keys of the bank, whether locked or not, can be still further depressed to a position which causes the corresponding contact member 14 to engage the contact member 13 of the key.

For numbering each of the push-button keys 38 38 a metal cap 28 is provided, to fit over a head 29 on the corresponding bar 37 to hold a number disk 30 and a transparent disk 31 in place, preferably as shown in Fig. 1. This construction permits of readily removing or changing the numbers of the various keys of the bank, which is a very desirable feature in intercommunicating telephone systems where the numbers of the various keys at the several stations have to be arranged to correspond with the numbers of the lines or stations of the system.

The spring-contact members 13, 14, 15, 16 and 17 of the various keys of the bank are all suitably mounted to the strips 33 33 by screws or bolts, and are insulated from each other and from the strips 33 33 by suitable insulating washers and bushings 39.

The wiring for the various keys of the bank is connected to the connection terminals provided at the lower ends of the various spring-contact members of the several keys.

We do not wish to limit this invention to all of the particular details of construction herein shown, as many modifications may be made therein without departing from the scope of the appended claims.

What we claim as our invention is:

1. A bank of switch keys comprising a plurality of push-buttons, a plunger for each of the push-buttons adapted to be operated thereby, a set of spring-contact members for each of the plungers adapted and arranged to be controlled thereby, a vertical bar for each of the keys connecting the push-button with the plunger, notches in each of the said vertical bars, one being beveled at its upper surface, a plurality of longitudinal side bars slidably mounted, a plurality of transverse locking bars carried by the said side bars, the said locking bars being adapted to normally

- rest in the notches of the said vertical bars, a leaf spring near one end of the bank of keys adapted to bear against one of the said transverse bars for forcing the latter as a unit into the said notches of the said vertical bars, and a coil spring acting on each of the said plungers to operate same when the latter are released, the depression of any one of the push-buttons causing the beveled surface of the notch associated therewith to operate the said locking bars and said side bars as a unit so as to disengage the said locking bars from the various notches of the said vertical bars whereby any of the push-button keys which may have been in depressed position are released, the said push-button which is being depressed being automatically locked in depressed position when depressed far enough to allow the said locking bars to be forced by the said leaf spring into the notches of the said vertical bars.
2. A bank of locking switch keys having a plurality of longitudinal side-bars and a plurality of transverse locking bars comprising a unit, operable as such, a plurality of plungers in locking relation with the said transverse locking bars, a leaf spring acting on a

transverse bar of the locking bar unit to operate the latter when released by the depression of any of the said plungers, and an adjustment screw for the said leaf spring whereby the tension of same acting on the said locking bar unit may be adjusted as desired.

3. A switch key of the character described comprising a nonconducting plunger, switch-contact members adapted to be operated by the plunger, switches adapted to be controlled by the switch-contact members, means whereby a partial depression of the plunger operates both of the switch-contact members to control respective switches, and means whereby a still further depression of the plunger operates only one of the switch-contact members still further to control an additional switch.

As inventors of the foregoing we hereunto subscribe our names in the presence of two subscribing witnesses, this 25th day of March, 1908

ELMER R. CORWIN.
CHARLES A. BALS.
